CARL ALBERT HIRTH, OF STUTTGART-CANNSTATT, GERMANY.

APPARATUS FOR MIXING AND PRESSING SMOKELESS POWDER.

1,180,850.

Specification of Letters Patent. Patented Apr. 25, 1916.

Application filed November 25, 1911. Serial No. 662,483.

To all whom it may concern:

Be it known that I, CARL ALBERT HIRTH, subject of the King of Wurtemberg, residing at Stuttgart-Cannstatt, Germany, have invented new and useful Improvements in and Relating to Apparatus for Mixing and Pressing Smokeless Powder, of which the following is a specification.

In the manufacture of certain kinds of smokeless powder the mass must be brought into contact with ether or similar liquids and intimately mixed therewith before it is given the desired shape of tubes, ribbons or the like in a press. Hitherto the mass has, 10 first of all been supplied to a mixing machine in which the ether was added. The mass thoroughly mixed with ether was then conveyed to the press and the ether vapors were afforded an opportunity of escaping, 15 in the mixing machine, in the conveyer mechanism and finally in the press. Consequently it was necessary to provide suitable obturating or absorption devices in these three appliances notwithstanding which the 20 vapors were still able to escape, particularly during transfer from one apparatus to the other. This defect is effectually obviated by the combined mixing apparatus and press which forms the object of the 25 present invention. This renders it possible to employ substances which either owing to their dangerous character or to their value should be kept inclosed as far as possible; the necessary floor space is also 30 largely reduced, no conveyer mechanism is necessary and finally economy in labor is effected.

The invention will now be described with reference to the embodiments thereof which 35 are illustrated by way of example in the accompanying drawing:

In the accompanying drawing, Figure 1 is an elevation partly in section; Fig. 2 shows a section on the line A—B of Fig. 1, 40 Fig. 3 is a fragmental elevation partly in section, and Fig. 4 is a plan, partly in section, of a detail.

The machine is composed of three similar cylinders 2, 3 and 4 revolving about a central column 1. In revolving the cylinders, each of them can be caused to occupy a position which was previously occupied by one of the two other cylinders. The cylinder 2 is shown in the position I (Fig. 3) in which 45 it is filled with the powder mass. Beneath

this cylinder is the fixed obturating plate 5 which is common to all three cylinders while above it the piston 6 of a suitable hydraulic preliminary pressing device 7 is located; when the cylinder has been charged this 50 piston descends and produces a cylindrical depression in the mass which extends almost to the plate 5 so that the mass is not only preliminarily pressed but also provided with a cavity for the reception of the ether. 55 In order to prevent the mass from escaping upward a cover may be provided which is provided with a central aperture for the passage of the piston 6. After this preliminary pressing operation the cylinder 2 60 with its charge is caused to occupy the position II by revolving it above the plate 5; this is the position which the cylinder 3 is 65 represented as occupying in Fig. 1 of the drawing. The revolution can be facilitated by supporting the ball bearing 8 of the body carrying the cylinders 2, 3 and 4 on elastic material such as leather or the like which, 70 when the compression pressure ceases, slightly lifts the cylinders from the plate 5. 75 In the position II the cylinder is located above a depression 10 in the table plate which contains a mixing arm 11 (Figs. 1 and 2) secured to a screw spindle 12. At its upper part the cylinder is closed by a cover 80 85 13 which is preferably also hydraulically applied and which is provided with a passage 14 for the admission of the ether and a passage 15 for the discharge of the air during the charging. It is preferable to 90 provide for the obturation of both passages by a single cone-shaped valve 16, mounted upon a valve rod and yieldably pressed in its seat by a coiled spring at the upper end 95 of the valve rod. The valve can be depressed by any desired means such as the cam and lever illustrated in Fig. 1. The ether admitted fills the previously formed cavity and thus from the commencement comes into contact with a large proportion of the 100 mass, thereby largely facilitating the mixing. The spindle 12 of the mixing arm is driven in any convenient manner for example by means of belts 17, one running right and the other crossed and running 105 left and which by means of gearing or the like drives the shaft 18 carried through the central hollow column 1 of the machine; at its lower end this shaft carries a toothed drum 19 which is in mesh with a gear wheel 110

20 on the mixing spindle 12. The thread of the mixing spindle in its rotary movement passes through a nut 21 which is held at least temporarily so that the mixing arm 5 receives a movement of translation along the axis of the cylinder 2 or 3. It thus traverses the cylinder first from below upward which insures certain advantages; then the direction of rotation and consequently 10 the movement of translation are reversed until the mixing arm has again entirely entered the depression 10 and allows the cylinder to continue its rotation to the position III. In order to obtain a uniform mixture 15 and simultaneously an even division of the mass provision is made enabling the mixing arm in its two end positions to carry out several rotations without advancing. The square-threaded nut 21, by which the 20 mixing spindle 12 is moved, is rotatably mounted on ball-bearings; during the upward and downward movement of the mixing arm this nut is held fast by the pawl 22 under inwardly directed spring pressure, 25 which pawl rests against the nose 24 of the threaded nut. Upon reaching the end of the upper or lower stroke a cone friction wheel 25, by pressing on a roller 26 of the pawl 22, disengages the latter. The nut is thus released, 30 which, due to the thread friction which is always greater than the friction in the ball bearings, rotates with the mixing spindle 12, and hence the mixing arm carries out a purely rotary movement. For 35 security the cone friction wheels 25 are each provided with a rigid stop 23, which forcibly rotates the nut 21 after release of the detent at the nose 24. The movement of the spindle 12 is advantageously reversed 40 by some suitable means acting automatically upon the completion of a given number of revolutions. When the mixing is completed the cylinder containing the mass is further rotated into the position III if desired beneath 45 a suitable cover which may be fixed and extend from II to III. In the position III it is located above a sieve-like die 28 and beneath a hydraulic press piston 29 which upon its descent forces the mass through the 50 die in the usual manner except for a portion which remains above the matrix in the form of "cake" in which is retained any foreign bodies which it may contain. The material forced through the die reaches a suitable table 30 or conveyer mechanism in a form corresponding to the perforations in the die. Preferably the die for the pressing operation is rigidly connected with the cylinder and after the pressing it is removed for cleaning purposes.

Naturally the position of the cylinder should be selected in such a manner that in all three cylinders, the three operations proceed simultaneously, that is to say, while 60 the mass is being charged and preliminarily

pressed in cylinder 2, ether is admitted to and mixed in cylinder 3 while in cylinder 4 the mass is forced out.

In addition to its employment for the manufacture of smokeless powder the machine described can also be utilized for example by adapting the construction to the special conditions for the manufacture of other products in which a mass is to be mixed with a liquid and the paste thus formed brought into its final form by pressing and possibly subsequent disintegration.

Having now particularly described and ascertained the nature of my said invention and in what manner the same is to be performed, I declare that what I claim is:—

1. In a machine for manufacturing smokeless powder, the combination of a piston; mixing device adapted to travel parallel to the axis of the piston; and a cylinder 85 adapted to be revolved successively into operative relation with the piston and the mixing device.

2. In a machine for manufacturing smokeless powder, the combination of a 90 pressing piston; a mixing device adapted to travel parallel to the axis of the piston; and a plurality of cylinders adapted to be revolved successively into operative relation with the piston and the mixing device. 95

3. In a machine for manufacturing smokeless powder, the combination of a mixing apparatus; and a group of cylinders adapted to be revolved into successive operative relation with the mixing apparatus. 100

4. In a machine for the manufacture of smokeless powder, the combination of a preliminary pressing apparatus; a mixing apparatus; a subsequent pressing apparatus; and a cylinder adapted to be placed in operative relation with each of said apparatus respectively. 105

5. In a machine for manufacturing smokeless powder, the combination of a preliminary pressing apparatus; a mixing apparatus; and a plurality of cylinders adapted to be revolved into successive coöperation with all of said apparatus. 110

6. In a machine for the manufacture of smokeless powder, the combination of a 115 cylinder adapted to hold a mass to be pressed; and a pressing piston of less diameter than the cylinder and adapted to be moved axially of the cylinder and pressed nearly therethrough so that in addition to a 120 preliminary pressing a cavity is formed in the mass.

7. In a machine for the manufacture of smokeless powder, the combination of a 125 pressing cylinder; a mixing means therein used in connection with the preliminary pressing apparatus for the cylinder; and a removable cover for said cylinder provided with a passage for the mixing liquid and a discharge opening for the air forced out. 126

8. In a machine for the manufacture of smokeless powder, the combination of a piston; a mixing device adapted to travel parallel to the axis of the piston; a cylinder adapted to be placed successively in operative relation to said piston and mixing device; and a cover adapted to cover the cylinder when in operative relation with the mixing device and provided with a passage for the mixing liquid; a discharge opening for the air forced out and a valve for said passage and opening.

9. In a machine for manufacturing smokeless powder, the combination of a piston; a mixing device adapted to travel parallel to the axis of the piston; a cylinder adapted to be revolved successively into operative relation with the piston and mixing device; and means for imparting movement of rotation and translation to the mixing device throughout the length of the cylinder, when in operative relation thereto.

10. In a machine for manufacturing smokeless powder, the combination of a piston; a mixing device adapted to travel parallel to the axis of the piston; a cylinder adapted to be revolved successively into operative relation with the piston and mixing device; and means for imparting movement of rotation and translation to the mixing device throughout the length of the cylinder, when in operative relation thereto and for continuing the movement of rotation and automatically arresting the movement of translation for a short period at the end portions of the movement of translation.

11. In a machine for manufacturing smokeless powder, the combination of a preliminary pressing piston; a mixing device adapted to move parallel to the axis of the piston; and a cylinder of greater diameter and length than the piston and adapted to be successively revolved into operative relation therewith and with the mixing apparatus.

12. In a machine for the manufacture of smokeless powder, the combination of a piston; a mixing device adapted to travel parallel to the piston; a cylinder adapted to be revolved into successive operative relation

with said piston and device; a cover above said device and adapted to cover the cylinder when in operative relation with the device, and provided with inlet and outlet closable openings; and means for holding the cover tight upon the cylinder.

13. In a machine of the character described, the combination of a preliminary pressing piston; a mixer cover provided with a closable opening; a forming piston; an obturating piece disposed a distance below said pistons and cover; a revolving member rotatably mounted between said plate and said pistons and cover and comprising a plurality of cylinders each one of which is adapted to be brought successively into register with the pressing piston, the cover and the forcing piston respectively; and a mixing means adapted to be disposed in the cylinder under the cover and to be moved up and down and rotated therein.

14. In a machine for the manufacture of smokeless powder, the combination of a preliminary pressing piston; a mixer cover provided with an inlet and a discharge opening; valves for closing said openings; a forcing piston; a stand supporting said pistons and cover at the upper part thereof; an obturating plate below and spaced from said pistons and cover and provided with a die below said forcing piston; a rotatable member mounted between said plate and said pistons and cover and comprising a plurality of cylinders each one of which is adapted to be brought into successive register with the pressing piston, the mixer cover and the forcing piston respectively; a mixing spindle passing through said plate co-axial with said cover; a mixing arm on the upper end of said spindle; and means for rotating the spindle and moving the same in an axial direction.

In testimony whereof I have signed my name to this specification in the presence of two subscribing witnesses.
